Specification for Design.

Patented July 13, 1920.

Application filed March 29, 1920. Serial No. 369,757. Term of patent 3½ years.

To all whom it may concern:

Be it known that I, JOHN ARCHER, a citizen of the United States, residing at No. 380 South Fourteenth street, San Jose, in the county of Santa Clara and State of California, have invented a new, original, and ornamental Design for a Badge, of which the following is a specification, reference being had to the accompanying drawing, forming part thereof.

The figure is a plan view of a badge, showing my design.

I claim:

The ornamental design for a badge as shown.

JOHN ARCHER.
